UNITED STATES PATENT OFFICE.

HENRI ABRAHAM, OF PARIS, FRANCE.

WIRELESS TELEGRAPHY.

Application filed September 2, 1921. Serial No. 498,018.

To all whom it may concern:

Be it known that I, HENRI ABRAHAM, citizen of the Republic of France, and resident of Paris, France, post-office address 47 rue 5 Denfert-Rochereau, have invented new and useful Improvements in Wireless Telegraphy, which improvements are fully set forth in the following specification.

The present invention relates to improvements in wireless telegraphy. The object of the invention is an installation by means of which, without the reduction of broadcasting area, two or a larger number of messages may be transmitted simultaneously 15 from the same antennae, the transmitting station working at full power for each of the simultaneous transmissions, and the transmission of each message being effected on a group of waves of characteristic wave-lengths.

Multiplex wireless telegraph systems have already been constructed, and in certain of these systems two groups of high-frequency waves are sent out at the same time, with a 25 different frequency for each of the two messages. Such system, however, involves the serious objection that the power must be divided between the two messages.

In the systems referred to, if only 30 kilowatts are available, the maximum that can be utilized for each message is 50 kilowatts, which would greatly reduce the effective broadcasting area. With the present invention, on the contrary, the broadcasting 35 station can be operated at full power for all of the messages at the same time.

In other known systems, high-speed commutators are used which, even in the transmission of a single message, cause the groups 40 of waves emitted by the antenna to be interrupted many hundreds of times per second. This presents the serious difficulty that half of the time is wasted, and the range of the broadcasting station is greatly decreased. 45 The range is still further reduced because all of the power of the station cannot be utilized even in sending a single message. Finally, this system is not applicable to large 50 stations, because it is not yet known how to successfully employ high-powered rotary commutators giving sufficiently rapid com-

mutations in high-frequency currents. The present invention involves none of these objections.

Moreover, this invention differs essentially 55 from prior known systems which permit the superposition of a wireless telephone message and a wireless telegraph message, but which are incapable of sending two telegraph messages. My improved system is 60 specially adapted for wireless telegraphy.

Let it first be supposed that only two 65 wireless messages are to be sent simultaneously. The first message is transmitted at a certain wave-length L^1 , and the second message at another wave-length L^2 . The transmitting devices (keys) may act independently for the two emissions, but the apparatus is so arranged that during the moments when the manipulations (effecting the 70 two emissions simultaneously coincide, the resultant emission is made at a third wave-length L^3 quite distinct from the two characteristic wave-lengths L^1 , L^2 . Thus the first message is transmitted at one time on 75 L^1 and at another time on L^3 ; the second message is transmitted sometimes on L^2 and sometimes on L^3 , the emissions being however, always effected at full power.

At the other end in the first receiving station, the arrangement is such that reception is effected equally well at wave-length L^1 as at wave-length L^3 . At the same time, in the second receiving station, reception takes 85 place equally well at either one or the other of the wave-lengths L^2 and L^3 .

Each of the receiving stations receives its message without interference by the other transmission, and there is no reduction in broadcasting area as the emissions are always 90 made at full power.

In the case of three simultaneous transmissions, the separate wave emissions are made at three wave-lengths L^1 , L^2 and L^3 , but the coincidence of two wave emissions 95 results in three further waves of lengths L^4 , L^5 and L^6 , respectively; while the coincidence of all three wave emissions furnishes a seventh wave-length L^7 . Each receiving 100 station is arranged to receive equally well at its own characteristic wave-length and at the three other wave-lengths resulting

from the coincidence of the wave emissions. The various receiving stations may be installed at the same locality and may have parts in common, such as antennæ or receiving frames or even oscillating circuits controlled for certain resonances.

Certain installations will hereinafter be described which may be used for sending and receiving but which, it should be well understood, are only given by way of example, in order to more clearly explain the invention.

The accompanying drawing shows by way of example diagrams of particular installations for the transmission and reception of two messages simultaneously.

In said drawing:

Figure 1 shows a transmitting station for two simultaneous transmissions from the same generating means.

Fig. 2 is a representation of an installation adapted to receive two different wave-lengths, receiving being effected by a single antenna.

Fig. 3 relates to a modification, in which reception takes place on two frames.

In Fig. 1, the antenna 1 and the self-inductance 2 of the antenna are arranged in series with the source of transmitting current 3 and the ground connection 4. Two auxiliary circuits 5 and 6 are excited by the circuit of the antenna, and the closing of the keys 7 or 8 causes a change in the length of the emitted waves. These auxiliary circuits may be provided with self-inductances or capacities and may be excited by direct or inductive coupling. The induction may be produced by the self-inductance of the antenna itself or by a separate winding. The more simple hook-up is shown in the figure. The self-inductance of the antenna 2 acts by induction on the circuits 5 and 6, and the coupling is so regulated as to obtain the desired changes of wave-lengths. The instruments represented by the keys 7 and 8 may be of any desired type, viz. single or multiple-break. Moreover, each of the circuits may be replaced by a group of relay circuits excited and worked simultaneously in such a manner that the keys 7 and 8 need only interrupt very weak currents. The manipulations may be effected by short circuiting a self-inductance or a capacity forming part of an oscillating circuit, and may be effected by hand or automatically.

In the arrangement shown in Fig. 2, i. e., receiving stations for two wave-lengths, receiving is effected from a frame or an antenna 1" and a ground connection 2". As shown in Fig. 2, the receiving station comprises two groups of multiple resonating circuits connected in series with the antenna 1". The latter is connected by a self-inductance 2 and a variable condenser 3" with the first group of resonating circuits

A, B and by a self-inductance 2' and a variable condenser 3'" with the second group of resonating circuits A', B'; the ground connection 2" being made from the discharge side of the inductance 2.

It is considered unnecessary to show and describe each group of resonating circuits, as the two groups are alike. One group—that located at the upper part of Fig. 2, for example—comprises an amplifying device or audion containing a filament 4", a grid 5" and a plate 6". The circuit of plate 6" contains a winding 7" which operates by reactance on the circuit 2, 3" and it also contains a winding 8" for coupling it by induction with a second resonating circuit. This latter is formed by the inductance 9" and the condenser 10", the terminals of which are also connected to the filament 11" and grid 12" of a second amplifying device or audion, the circuit of which contains a reactance 14". The plate batteries are represented at *a* and *b*, and the heating battery at *c*.

The other group of resonating circuits is identical with the first one, excepting that it is tuned for a different wave-length.

The two condensers 10" and 10'" are connected to the filaments 15', 15" and to the grids 16', 16" of two other amplifying devices or audions. The plates of these two latter audions are fed, across one and the same resistance 22' or a single self inductance, by a battery *d*.

There is need to remark that the audion 11", 12", 13" of one group and, similarly, the audion 11'", 12'", 13'" of the other group are utilized exclusively to produce reactance by the circuits 14", 14"'; and that entirely different audions (15', 16', 20' in one group and 15", 16", 20" in the other group) are employed to respectively connect the oscillating circuit 9", 10" on the one hand, and 9'", and 10'" on the other hand with the rest of the apparatus.

The receiving apparatus comprises an amplifying device or audion 25, 26, 27. The electro-magnet 28 of the receiving apparatus is arranged, as shown, between the plate 27 of the device and the positive pole of the plate battery *e* which has been represented as separate from the battery *d*, but which could be combined with it.

The grid 26 is connected at one side to the filament 25 by the resistance 29, and at the other side to the plates 20', 20" by the condenser 30, as usual in wireless installation.

The oscillating circuits A—B and A'—B' having been tuned to resonate respectively for the two wave-lengths to be received at the station, it can be seen that they receive exclusively only on one or equally well on the other wave-length.

Fig. 3 shows, as already mentioned above,

a practical embodiment of a receiving apparatus in which receiving is effected by two frames 1, 1'. The same elements are represented in this figure as are shown in

5 Fig. 3.

It should be clearly understood that the installations hereinbefore described are given solely by way of examples, and that the arrangements may be varied as desired 10 without departing from the spirit or scope of the invention.

I claim as my invention:—

1. A system of radiotelegraphy, for simultaneously transmitting several messages in 15 the same direction from a single sending station, each message at full power so as to avoid decreasing the sending area, comprising a series of independent manipulating devices at the sending station so arranged that 20 by manipulating one of said devices emissions are produced at the wave-lengths characteristic of that device, and that when another device is manipulated the emissions have wave-lengths which are characteristic 25 of the second device and different from those of the first device; and a series of receiving devices at the receiving station equal in 30 number to the manipulating devices at the sending station, each receiving device being so arranged as to be capable of receiving 35 equally well at a predetermined series of different wave-lengths which are the same as those sent out by the sending station when a certain manipulating device is operated.

2. A system of radiotelegraphy, for simultaneously transmitting several messages in the same direction from a single sending station, each message at full power so as to avoid decreasing the sending area, comprising 40 a series of independent manipulating devices at the sending station so arranged that by manipulating one of said devices emissions are produced at the wave-lengths characteristic of that device, and that when 45 another device is manipulated the emissions have wave-lengths which are characteristic of the second device and different from those of the first device; and a series of receiving devices at the receiving station equal in 50 number to the manipulating devices at the sending station, each receiving device comprising resonating circuits connected with the grids of amplifying devices, the anodes of which are fed with electric current across 55 one and the same translating device.

3. A system of radiotelegraphy, for transmitting a plurality of signals at full power at the same time and in the same direction, comprising a sending station adapted to 60 send each group of signals at a wave-length characteristic for that group, and coinciding groups at resultant characteristic wave-lengths distinct from any of the other characteristic wave-lengths; and a receiving station adapted to receive each group of signals

at the characteristic wave-length of that group, and at any of the characteristic wave-lengths produced by the coincidence of groups of signals.

4. A system of radiotelegraphy, for transmitting and receiving a plurality of signals at full power at the same time and in the same direction, comprising a sending station provided with a single set of antennæ, a source of oscillating current, and a series of 70 devices reacting on the oscillating current and altering the frequency thereof so as to send each group of signals at different characteristic wave-lengths; and a receiving station provided with a receiving device adapted to receive equally well at a predetermined series of wave-lengths which are the same as those sent out by the sending station for 75 one group of signals.

5. A system of radiotelegraphy, for transmitting and receiving a plurality of signals at full power at the same time and in the same direction, comprising a sending station provided with a single set of antennæ, a source of oscillating current, and a series 80 of devices reacting on the oscillating current and altering the frequency thereof so as to send signals at different characteristic wave-lengths, and coinciding groups at resultant characteristic wave-lengths distinct 85 from any of the other characteristic wave-lengths; and a receiving station provided with means for receiving each group of signals at the characteristic wave-length of that group, and at any of the characteristic 90 wave-lengths produced by the coincidence of groups of signals.

6. A system of radiotelegraphy, for transmitting and receiving a plurality of signals at full power at the same time and in the same direction, comprising a sending station provided with a single set of antennæ, a source of oscillating current, and a series of devices reacting on the oscillating current and altering the frequency thereof so as to 105 send signals at different characteristic wave-lengths; and a receiving station provided with a plurality of resonating circuits, each tuned to a predetermined frequency, an amplifying device connected to each resonating circuit, and a translating device common to said resonating circuits and traversed by alternating current each time the apparatus receives waves of the characteristic 110 wave-lengths.

7. A system of radiotelegraphy, for transmitting and receiving a plurality of signals at full power at the same time and in the same direction, comprising a sending station provided with a single set of antennæ, a source of oscillating current, and a series 125 of devices reacting on the oscillating current and altering the frequency thereof so as to send signals at different characteristic wave-lengths, and coinciding groups at resultant 130

characteristic wave-lengths distinct from any of the other characteristic wave-lengths; and a receiving station provided with a plurality of resonating circuits, each tuned to a predetermined frequency, an amplifying device connected to each resonating circuit, and a translating device common to said resonating circuits and traversed by alternating current each time the apparatus re-

ceives waves of the characteristic wave-lengths.

In testimony whereof I have signed this specification in the presence of two subscribing witnesses.
